UNITED STATES PATENT OFFICE.

VICTOR G. JENSEN, OF CHICAGO, ILLINOIS.

FUSE.

1,266,479.

Specification of Letters Patent. Patented May 14, 1918.

Application filed September 18, 1916. Serial No. 120,841.

To all whom it may concern:

Be it known that I, VICTOR G. JENSEN, a citizen of the United States, and a resident of the city of Chicago, in the county of Cook and State of Illinois, have invented certain new and useful Improvements in Fuses; and I do hereby declare that the following is a full, clear, and exact description of the same, reference being had to the accompanying drawings, and to the numerals of reference marked thereon, which form a part of this specification.

Inclosed or cartridge fuses usually consist of a fusible strip or wire placed within a tubular inclosing jacket filled with porous, powdered or other insulating material through which the fuse wire is suspended from end to end surrounded by said insulating material. The wire, tube and insulating material are made into one complete or unitary, self-contained device with brass or copper ferrules at each end to which the fuse wire is soldered. When this type of cartridge fuse blows, by excessive current or a short circuit the gases resulting are either taken up by the insulating filling of the tube, or escape through an opening in the side of the tube. In both of these cases the complete fuse must be removed from the circuit and replaced.

This invention relates to an improved type of cartridge fuse comprising recessed insulating members adapted to be removably clamped together by end ferrules to retain a fusible strip therebetween passing through said recessed portions and with the end ferrules formed to contact the ends of said fusible strip and acting as terminal contact means to connect the fuse in circuit. Said fuse is constructed to permit the replacement of the fusible strip after the same has blown, or the replacement of any of the other parts of the fuse.

It is an object of this invention to construct a cartridge fuse comprising replaceable members.

It is also an object of this invention to construct a cartridge fuse adapted to be taken apart to permit the replacement of the fusing member and the reuse of the remaining parts of the fuse.

It is also an important object of this invention to provide a cartridge fuse wherein the fusible strip is removably clamped between insulating members which are in turn clamped together at their ends by metal fer-

rules constructed to contact said fusible strip and acting as contact terminals for connecting the fuse in a circuit.

It is a further object of this invention to construct a cartridge fuse wherein semi-cylindrical insulating members are recessed to receive an irregularly shaped fusible strip and to afford a blowing or explosion chamber, said members being formed to receive ferrules on the ends thereof to releasably clamp the same together and contact the ends of said fusible strip.

It is finally an object of this invention to provide an inclosed or cartridge fuse adapted to receive the fusible strip of only one particular size or capacity, said fusible strip or any of the parts of said fuse being so formed that they may be removed or replaced.

The invention (in a preferred form) is illustrated in the drawings and hereinafter more fully described.

In the drawings:

Figure 1, is a side elevational view of a cartridge fuse embodying the principles of my invention.

Fig. 2, is a cross-section taken on line 2--2, of Fig. 1.

Fig. 3, is a section taken on line 3--3, of Fig. 2, with parts shown in elevation.

Fig. 4, is an inside view of one of the insulating members of the device having fusible strip removably embedded therein.

Fig. 5, is a view taken on line 5--5, of Fig. 3, with parts omitted.

Fig. 6, is an inside view of the ferrule at one end of the device.

Fig. 7, is an inside view of the other end ferrule with a spring therein.

As shown in the drawings:

The main body of the cartridge fuse comprises semi-cylindrical solid insulating members 1 and 2, having centrally formed or cut in the inner face thereof recesses 3 and 4, respectively adapted when said insulating members are placed face to face to register with one another to form a fusing or explosion chamber as clearly shown in Figs. 2 and 3. Each of said insulating members 1 and 2, has integrally formed along one side of the inner face thereof a rib 5, and along the opposite side parallel to said rib a groove 6, complementary in shape to said rib. The rib of one member is adapted to fit into the groove of the other to prevent a lateral movement and hold said members aligned. The

outer surface at one end of each of said insulating members is provided with threads 7, while the other end has a circumferential groove 8, formed or cut therein. The inner 5 portion of each of said insulating members at the end where said groove 8, is located, is cut away to reduce the thickness thereof, as indicated by the reference numeral 9. Cut or formed longitudinally in the inner face 10 of the insulating member 1, and communicating with the recess 3, is an irregularly shaped or zigzag groove extending through the entire length of said member, and adapted to receive seated therein, flush with 15 the inner surface thereof, a flattened fusible strip or wire 10, also zigzag in shape the central part at the point 11, passing through the recess 3. Said fusible strip 10, has integrally formed on each end thereof an enlarged rounded portion having a slit 12, 20 therein to afford contact members or tongues 13, adapted to be bent in opposite directions from one another flat over the respective ends of said insulating members, 25 as shown in Figs. 3 and 5.

To removably hold the insulating members 1 and 2, together with the fusible strip 10, therebetween, the reduced ends 9, are brought together while the opposite ends are 30 spread apart to permit a metallic ferrule or cap 14, having a circumferential bead or rib 15, integrally formed on the inner periphery thereof, to slip or engage over the reduced ends 9, with the bead 15, fitting into the 35 grooves 8. In order to form a suitable connection between the tongues 13, and the ferrule 14, a convex star shaped metallic spring or convex connecting spider 16, is mounted in said ferrule with the convex surface there- 40 of bearing against the tongues 13.

The threaded end of said insulating members 1 and 2, are now brought together forcing the sides of the reduced ends 9, tightly against the inner surface of said ferrule 14, 45 with the bead 15, engaging the grooves 8, and forcing the resilient spring 16, tightly against the tongues 13, thus insuring a good electrical contact and also preventing the removal of the ferrule 14. To clamp the 50 threaded ends of said members 1 and 2, together an internally threaded metallic ferrule or cap 17, is removably engaged over the threads 7. Integrally formed on the inner surface of the base of said ferrule 17, 55 are a plurality of concentric knife edge ridges 18, adapted to tightly contact or cut into the tongues 13, to form a good contact as the ferrule 17, is threaded into said insulating member. To permit the cartridge 60 fuse to be detachably connected in a suitable support in a circuit, each of said ferrules 14 and 17, has integrally formed thereon an outwardly projecting lug 19.

The operation is as follows:

65 In assembling the cartridge fuse a zigzag

fusible strip 10, of the required ampere capacity is placed in the zigzag groove in the insulating member 1, said groove being so shaped as to receive only a certain fusible strip of a rated capacity and shape to 70 prevent fusing strips of either a larger or smaller capacity being used, thereby causing improper fusing of the circuit in which the cartridge fuse is to be used. With the fusible strip 10 seated in said member 1, the insulating member 2, is placed thereagainst 75 with the recesses 3 and 4, registering with one another to form a fuse blowing chamber, having the central portion 11, of the fusible strip 10, passing therethrough. The 80 reduced ends 9, of said members 1 and 2, are now brought together to permit the ferrule 14, to be inserted over said ends, with the bead 15, engaging in the grooves 8, and with the convex spring contact member 16, 85 pressing against the bent over tongues 13. The threaded ends 7, of said members are now pressed together thus forcing the reduced ends 9, outwardly against the inner surface of said ferrule and also forcing the 90 tongues 13, tightly against the spring 16, to insure a good contact. In this position the rib 5, and groove 6, of the insulating member 1, fit into the respective groove and rib of said member 2, to hold said members 95 alined and prevent any lateral movement therebetween. The ferrule 17, is now threaded onto the threaded ends 7, of said members, the knife edge ridges 18, of said cap pressing or cutting into the tongues 13, 100 rigidly holding the same against the ends of said members and producing a good contact between the cap 17, and the fusible strip 10. The cartridge fuse may now be mounted in a suitable fuse support adapted 105 to receive the lugs 19, whereby the fuse is connected in circuit.

If the circuit is subjected to an excessive current or a short circuit, the fusible strip 10, will blow in the explosion chamber 11 formed by the recesses 3 and 4, said chamber retaining the gases resulting from the blowing of the fusing strip. The ferrules 17 and 14, may now be removed and the insulating members 1 and 2, separated and 11 cleaned, removing the blown fusing strip 10, and replacing the same by another fusing strip of the same capacity, thus permitting the reuse of the other parts of the cartridge fuse, any of which may of course 12 be replaced if they become defective.

I am aware that various details of construction may be varied through a wide range without departing from the principles of this invention, and I therefore do 13 not purpose limiting the patent granted otherwise than necessitated by the prior art.

I claim as my invention:

1. In a cartridge fuse of the class described, interfitting insulating members, a 1

zigzag fusing strip removably embedded in one of said members, and mounting means contacting the ends of said fusing strip and removably clamping the adjacent ends of 5 said members together to permit replacement of said fusing strip after the same has been blown.

2. In an inclosed fuse of the class described, insulating means, a removably fusing strip passing therethrough and bent over the ends thereof, a ferrule, a convex spring therein, said ferrule adapted to be removably engaged over one end of said insulating means to permit said convex spring 10 to contact one end of said fusing strip, a second ferrule, concentric ridges integrally formed therein, said second ferrule adapted to engage over the other end of said insulating means with said ridges contacting the 15 other end of said fusing strip, and means on said ferrules for mounting the inclosed fuse.

3. In a cartridge fuse of the class described, an irregularly shaped fusing strip 25 of a given current capacity, recessed insulating members irregularly grooved to removably receive said fusing strip, each of said members cut away and having a groove at one end thereof and threads at the other 30 end, a cap, a bead integrally formed therein, a spring in said cap, said cap adapted

to engage over the grooved ends of said members when the cut away ends are brought together with said bead fitting into 35 said grooves and with said spring contacting one end of said fusing strip, an internally threaded cap, ridges integrally formed therein, said cap adapted to be threaded over the threaded ends of said members with said ridges contacting the 40 other end of said fusing strip, and means integrally formed on said caps for mounting the cartridge fuse.

4. A fuse comprising interfitting insulating members threaded at one end and 45 shaped at their opposite ends to receive a cap thereon, a fuse strip between said members having the ends bent over the ends of said members, a cap threaded on the threaded end of the insulating members firmly, clamping the end of the fuse in place, a cap on the opposite end of the members complementally formed to receive said end 50 therein, and a tension member in the cap bearing on the end of the fuse. 55

In testimony whereof I have hereunto subscribed my name in the presence of two subscribing witnesses.

VICTOR G. JENSEN.
